(57) **CLAIM**

The ornamental design for a mausoleum, as shown and described.

DESCRIPTION

FIG. 1 is a perspective view showing my new mausoleum;

FIG. 2 is a front view thereof;

FIG. 3 is a back view thereof;

FIG. 4 is a top view thereof;

FIG. 5 is a bottom view thereof;

FIG. 6 is a left view thereof, with the right side being a mirror image; and,

FIG. 7 is an enlarged cutaway view of one of the height adjustment mechanisms.

The evenly spaced broken lines depict portions of the mausoleum that form no part of the claimed design. The dot-dot-dash broken line squares depict the limits of the enlarged views and form no part of the claimed design.
